UNITED STATES PATENT OFFICE

2,495,026

HYPODERMIC SYRINGE

Arthur E. Smith, Los Angeles, Calif.

Application September 14, 1946; Serial No. 697,075

1 Claim. (Cl. 128—220)

1

This invention relates to improvements in hypodermic syringes of a type in which the medicinal compound is by the manufacturer delivered in a sterilized cartridge, commonly termed an ampule, mountable on the syringe and axially slideable thereon for the purpose of injections, such as common in medical practice.

It is the general object of the invention to provide a simple inexpensive and efficient syringe for administering hypodermic medicinal compounds or solutions such as penicillin-oil-wax. A further object is to provide a device including an ampule for the medicinal compound of such inexpensive construction that it may be discarded upon completion of the injection. Another object is to provide a device which may be quickly taken apart for cleaning and sterilization. A still further object is to provide means for tightly covering the needles of the device so as to maintain the needles in a sterile condition, and also in order to protect the needles from injury or breakage. Another object is to provide a device, the parts of which may be manipulated during the operation of administering a medicinal compound to determine whether or not the needle accidentally has entered a blood vessel. Another object of the invention is to provide an injection needle with means for producing a fluid tight joint, also means to prevent dislodgment of the needle during injection of a medicinal compound into the patient. These and other objects and the many advantages of the invention will be better understood from the following detailed description and by referring to the accompanying drawings of which:

Fig. 1 is a general view of the needle holder or syringe proper of the invention;

Fig. 2 is a substantially corresponding view taken in the direction of the arrow 2 of Fig. 1;

Fig. 3 shows the completely assembled device as it appears when ready for use;

Fig. 4 shows the front end of the needle holder; and

Fig. 5 illustrates the rear end thereof;

Fig. 6 is a sectional side view of the ampule of the invention;

Fig. 7 is an end view of this ampule;

Fig. 8 is a sectional view of a member of the ampule as it appears when separated therefrom; and

Fig. 9 illustrates a stylet which is insertable through the needles of the device when the syringe is not in use, thereby to prevent clogging the lumens of the needles.

The structure of the invention, in the form il-

2

lustrated in the drawings, comprises generally a needle holder A and a container or ampule B for a medicinal compound.

The needle holder, or syringe proper, consists of a cylindrical body 1 through the lumen of which extends a needle 2. The front end of the body is shown somewhat tapered, substantially as indicated at 1^a, and it is fitted with screw threads 1^b at the root of the tapered portion thereof.

The needle, as a whole, is in this device made in two parts, namely, the above named inner needle end 2, and an injector portion or needle 3. The latter is supported by a tubular head 4, the inner end of which is recessed to form therein a tapered seat 4^a for the tapered end portion 1^a of the body, and screw threads 4^b are provided at the entrance to the recess for engagement with the threads 1^b of the body.

When the needle head is screwed in position on the end of the body, it is found that a fluid tight joint is provided and that the two parts of the syringe become firmly interlocked, which prevents the needle from becoming dislodged during injection.

The ampule B consists of a short tube 5, made from transparent material and fitted at one end with a soft-rubber closure 6, which is internally recessed to provide a central diaphragm 6^a. In the tube 5 is seated a piston 7, and this piston is internally threaded, or fitted with a metal insert 8 which is internally threaded to receive the screw threads of a shoulder portion 1^c at the inner end of the syringe body 1.

The ampule is designed to hold a given quantity of any desired medicinal compound such as penicillin-oil-wax and this compound is, by the manufacturer, injected through a hypodermic needle (which is projected through the diaphragm 6^a) into the space 9 between the piston 7 and the closure 6. It is important to note that the piston 7 is slidable within the ampule to determine the quantity of medicinal compounds to be injected therein.

In order to mount the ampule in position, it is merely required to place the open end thereof over the end of the syringe body 1 and to advance the ampule on the body until the inner needle 2 passes through the threaded perforation 50 of the insert 8 and the shoulder 1^c reaches this perforation, whereupon a few relative turns causes the shoulder to seat tightly within the insert and the end of the needle to penetrate the diaphragm 7^a of the piston. By referring to Fig. 5, it is noticed that the end of the needle 2 after

penetrating the diaphragm 7^a extends into the recess 7^b of the piston until the point of the needle is flush with the end of the piston. The assembled syringe is now ready for use.

A sheath 11 is placed over the injection needle and this sheath is made with internal screw threads which engage a threaded shoulder 4^c of the needle holder 4 to lock the sheath firmly in position thereon. As a further protection, a stylet 12 is inserted through the lumens of the needles 2 and 3. This stylet is fitted with a knob 13 which is internally threaded to engage the threads of the body shoulder 1^c, which locks the stylet firmly in position thereon. The unit in this manner assembled should now be sterilized and retained for future use.

To operate the syringe, the sheath 11 is removed from the threaded portion 4^c and needle 3 is inserted to the proper depth into the tissues of the patient, whereupon a check should be made to determine whether or not the end of the needle has punctured a blood vessel. Such check is effected simply by a slight withdrawing movement of the ampule which causes suction because of the vacuum created.

If the point of needle 3 has punctured a blood vessel, blood will be aspirated into space 9 of ampule B. Because injection of the compound into a blood vessel might prove fatal, it is seen that such check by retraction of the ampule forms a most important feature of the invention.

Having successfully completed the check, it is merely required to force the ampule forward over the syringe body 1 by placing the thumb over the closure 6 and holding the hexagonal grip 10 of the body between the first and second fingers. The piston 7 is thereby caused to advance within the ampule until the convex end thereof comes to rest within the concave recess 6^b of the closure 6. All of the compound has now been ejected 40 from the ampule without leaving any waste whatever, which completes the injection. The empty ampule is then unscrewed and discarded.

This application is a continuation-in-part of my co-pending application Serial No. 680,748, filed July 1, 1946.

I claim:

A syringe including a medicament holding ampule, said ampule comprising a cylindrical body, a closure at one end of said body; a plunger movable relative to and slidably in said ampule, said plunger comprising an elongated body fixedly mounting an inner needle and having a threaded inner end portion, a piston stopper having a threaded recess, the threaded inner end portion being adapted to engage the piston stopper threads, means closing the inner end of said threaded recess, said plunger having an exteriorly threaded outer end, a tubular head having an axial bore therethrough and having its inner end interiorly threaded and being adapted to engage the outer end threaded portion of said plunger, said inner needle in the plunger bore having an inner end adapted to be disposed in the threaded recess of said piston stopper, an injector needle having a sharpened outer end and having an inner end seated within said tubular head, said plunger being rotatable relative to the piston stopper to cause the inner end of the inner needle to pierce the piston stopper closing means to thereby place the inner needle in communication with the contents of the ampule whereby the contents of the ampule may be discharged through the inner needle, the tubular head, and the injector needle.
